UNITED STATES PATENT OFFICE.

HERBERT O. RUSSELL, OF DETROIT, MICHIGAN, AND CHARLES LEIGH PAULUS, OF DAYTON, OHIO.

GENERATOR FOR SYNCHRONIZING GEAR.

Application filed April 18, 1922. Serial No. 555,409.

To all whom it may concern:

Be it known that we, HERBERT O. RUSSELL and CHARLES LEIGH PAULUS, citizens of the United States, residing, respectively, at Detroit and Dayton, in the counties of Wayne and Montgomery and States of Michigan and Ohio, have invented certain new and useful Improvements in Generators for Synchronizing Gear, of which the following 10 is a specification.

This invention relates to an impulse generator for synchronizing gear and is designed especially for use on airplanes, the generator being driven by the engine and 15 serving to transmit impulses to the trigger motor of a machine gun enabling said gun to fire through the zone of the propeller without the bullets striking the propeller blades.

20 By a novel arrangement herein shown and described, a plurality of impulse generators may be mounted one upon the other so that all of them will be driven by the engine, the arrangement being such that a plurality of 25 machine guns may be controlled and fired; furthermore said guns may be arranged at any convenient locations on the aircraft.

A further object of the invention is to 30 provide a means whereby each of the generators may be adjusted independently of the others for the purpose of regulating the time of firing of the gun controlled thereby.

With the above and other objects in view, 35 the invention consists in the novel construction, combination and arrangement herein described, illustrated and claimed.

In the accompanying drawings;

Figure 1 shows the impulse generator in elevation.

40 Figure 2 is a diametrical section through the same.

Figure 3 is a horizontal section through the generator taken in line with the cam and impulse cable.

45 The generator comprises a housing 1 which is of general cylindrical formation and provided with a vernier flange 2 at the base thereof having a circular or arcuate series of holes 3 to adapt the housing to be 50 adjusted and accurately and securely fastened in any position. This enables the impulse generator to be adjusted or set so that the firing operation of the gun will take place and insure against the bullets striking 55 the blades of the propeller.

Extending co-axially within the housing is a cam shaft 4 having a square lower portion 5 and provided with a square socket 6 in the upper portion thereof, the object being to enable one or more generators to 60 be placed upon each other and interconnected by the cam shafts so as to be simultaneously driven. The shaft 4 carries a cam 7, which is illustrated as having two projections which are adapted to come in contact with one end of a cam lever 8, mounted centrally upon the pivot 9 within the housing 1. The other end of the cam member 8 works in a notch or slot 10 in the end piece 11 of a flexible impulse cable 12 which extends to the trigger motor of the gun controlled by said generator. The cam lever 8 works in an off-set 13 of the housing 1 as best shown in Figure 3.

The cam shaft 4 is journaled in antifriction bearings 14 within the housing, a lubricant being fed in said bearings through an oil cup 17. The housing 1 is furthermore provided with a second vernier flange 15 having holes 16 to enable another impulse generator mounted thereon to be adjusted actually around the center of the shaft 4 so as to regulate the time of firing of the gun controlled thereby.

It will be understood that the generator, 85 driven by the engine of the airplane and transmitting impulses to the trigger motor of the machine gun, allows the gun to fire through the zone of the propeller without the bullets striking the propeller blades. 90 Movement of the cam lever, due to the hump of the cam, imparts a reciprocatory motion to the impulse cable, thus controlling the firing of the gun. One or more generators may be placed one upon another and so adjusted as to regulate the time of firing of each gun controlled thereby, such an adjustment being rendered practical by the vernier flange. The generator is ordinarily connected with the trigger motor of the machine gun by a wire cable operating within a flexible steel or brass tube 1 bricated with graphite or oil. Such flexible tube enables the guns to be located at any necessary place on the airplane without reference to the location of the generator as the flexible tube may be bent and lead to any desired point. The gun is operated by a positive pull upon the impulse cable and not by means of energy stored in the springs. The impulse 100 105 110

cable is returned to its normal position after being pulled by the cam lever by means of a spring in the trigger motor.

Having thus described our invention, we claim:

1. In an impulse generator for synchronizing gear, a housing, an engine driven shaft rotatable therein, a cam on said shaft, an impulse cable, a cam-operated lever in said housing actuated by said cam and actuating the impulse cable, and means including a series of perforations in a flange on said housing for adjusting said housing around the axis of the cam shaft. 10
15. 2. In an impulse generator for synchronizing gear, a housing, an engine-driven cam shaft rotatable therein, a cam on said shaft, an impulse cable, and a cam-operated lever in said housing actuated by said cam and actuating the impulse cable, said housing having a flange provided with a series of perforations so spaced as to provide a vernier adjustment of said housing around the axis of said cam shaft.
20. 3. In an impulse generator for synchronizing gear, a housing, an engine-driven cam shaft rotatable therein, a cam on said shaft, an impulse cable, and a cam-operated lever
- in said housing actuated by said cam and actuating the impulse cable, said housing having at opposite ends thereof flanges having means permitting a fixed and exact adjustment of said housing around said cam shaft. 30
35. 4. In an impulse generator for synchronizing gear, a housing, an engine-driven cam shaft rotatable therein, a cam on said shaft, an impulse cable, and a cam-operated lever in said housing actuated by said cam and actuating the impulse cable, said cam shaft having flanges on a non-circular end portion 40 to fit into the non-circular portion of the shaft of an adjacent impulse generator.
45. 5. In an impulse generator for synchronizing gear, a housing, an engine driven cam shaft rotatable therein, a cam on said shaft, an impulse cable, a cam-operated lever in said housing actuated by said cam and actuating the impulse gear, said cam shaft having an end portion adapted to be fitted with an end portion of an adjacent impulse generator shaft in such a manner as to rotate the same. 50

In testimony whereof we affix our signatures.

HERBERT O. RUSSELL.
CHARLES LEIGH PAULUS.
